(57) **CLAIM**

The ornamental design for a walking cane handle, as shown and described.

DESCRIPTION

FIG. 1 is a top perspective view of a walking cane handle in accordance with the present design, shown in use attached to a cane;

FIG. 2 is a top perspective view of the walking cane handle of FIG. 1;

FIG. 3 is a bottom perspective view thereof;

FIG. 4 is a right side view thereof;

FIG. 5 is a left side view thereof;

FIG. 6 is a front view thereof;

FIG. 7 is a rear view thereof;

FIG. 8 is a top view thereof; and,

FIG. 9 is a bottom view thereof.

The broken lines shown in the drawings illustrate portions of the walking cane handle that form no part of the claimed design.
